SOFT LUGGAGE

Leslie Marshall, 15 Pine St., Woodmere, N.Y. 11598

Filed Nov. 28, 1969, Ser. No. 20,316

Term of patent 14 years

Int. Cl. D3—01

U.S. Cl. D87—5

FIG. 1

FIG. 2

FIG. 3

FIG. 1 is a rear perspective view of the soft luggage embodying my design;

FIG. 2 is a frontal perspective view of the soft luggage embodying my design; and

FIG. 3 is a bottom view of the soft luggage embodying my design.

The dominant feature of my design resides in the provision of a carrying handle disposed on the side of the bag opposite the side at which the draw string-carrying sling is secured. As shown in FIG. 2, patch pockets are provided at either side of the carrying handle.

I claim:

The ornamental design for soft luggage, as shown and described.
